UNITED STATES PATENT OFFICE.

GUSTAF AVID ANDERSON, OF WAYNESBORO, PENNSYLVANIA, ASSIGNOR TO LANDIS MACHINE COMPANY, OF WAYNESBORO, PENNSYLVANIA, A CORPORATION OF PENNSYLVANIA.

CUTTER-HEAD.

2,227,008

Specification of Letters Patent. Patented Jan. 6, 1920.

Application filed August 14, 1918. Serial No. 249,894.

To all whom it may concern:

Be it known that I, GUSTAF A. ANDERSON, a citizen of the United States, residing at Waynesboro, Franklin county, and State of Pennsylvania, have invented and discovered certain new and useful Improvements in Cutter-Heads, of which the following is a specification.

My said invention consists in certain improvements in the details and construction and arrangement of parts of cutter-heads of that particular type illustrated in Patent No. 1,289,721, granted December 31, 1918, on the application of Henry L. Fisher, whereby improved efficiency in the supports for the cutter or chaser holding slides is provided and other advantages in operation and result insured, all of which will be hereinafter more fully described and claimed.

20 Referring to the accompanying drawings which are made a part hereof and on which similar reference characters indicate similar parts,

Figure 1 is a face view of a cutter-head, 25 of the type referred to, the right hand portion of the view showing the cutter-head complete and the left-hand portion showing the cam ring and the retaining ring broken away and the cutter holding slides removed,

30 Fig. 2, a perspective view of one of the cutter holding slides;

Fig. 3 a detail cross section on the dotted line 3—3 in Fig. 1,

Fig. 4, a detail cross section on the dotted line 4—4 in Fig. 1,

Fig. 5, a detail cross section on the dotted line 5—5 in Fig. 1, and

Fig. 6 a detail on the dotted line 6—6 in Fig. 1.

40 In said drawings the portions marked A represent the body of the cutter-head, B the cam ring, and C the cutter or chaser holding slides.

The body A is an annular casting having 45 a projecting flange a on its back for attachment to the machine and a radial lug 10 on one edge on which the operating lever is pivoted.

The cam ring B is an annulus mounted 50 in a recess or on bearings (to be presently more fully described) on the face of said body A and is adapted to oscillate thereon, being held in position by a retaining ring 11 set into a recess formed partly in the body A and partly in the ring B and se-

cured in position by numerous screws 30 as shown.

Said cam ring B is formed with cam grooves 12 in its underface corresponding in number to the number of cutter or chaser holding slides. Body A is formed with a series of grooves 13, six being shown, which extend in a direction tangential to the work, or with the adjacent grooves at an angle to the other which is less than a right angle. 65 Each of said grooves is formed with "stepped" sides and has flat plates or gibs 14 secured on its opposite sides on top of the ledges or steps a distance above its bottom, the inner edges of said gibs overhanging the bottoms of the grooves. These gibs are secured on the seats thus formed by means of screws 15 extending through from the back side of the head and engaging with screw-threaded perforations in said gibs. 70

The cutter holding slides C have cutters or chasers c secured thereon in a manner clearly illustrated in Fig. 2 and common with the "Landis" type of cutter-head. Each cutter-holder is L-shaped consisting of 80 a long base with an off-set and appropriately formed head to afford the necessary support for the cutter adapted to bear against abutments on the body. Its under side is formed in the form of a T, or with 85 a channel in each side forming two flanges on each side, the base flanges 16 being much narrower than the outer flanges 17. Said holders fit in grooves in the body with the head of the T formed by the flanges 16 engaging the bottom surface R of the ways in the headbody and the opposing faces of gibs 14. Clearance is arranged for between the other faces of gibs 14 and the large flange 17, so that after slight wear the 90 steps can be "scraped" off, thus restoring the fit between flanges 16 and their grooves. Each of said cutter-holders has a pin 18 which engages pivotally with a sliding block 19 mounted in one of the cam grooves 12 of 100 the cam ring B.

Said cam ring B has a projection 20 on one edge in which is formed a segmental slot 21, a pivot pin 22 is clamped in said slot by means of a nut and a link 24 is 105 pivoted thereon. A bell-crank lever 25 is mounted on pivot 26 in the lug 10 on the frame A and is hinged by a pintle 27 to the end of said link 24. It will thus be seen that the swinging of lever 25 will os- 110

cillate cam ring B, and through its connection, by means of the blocks 19 and pivots 18 with the cutter holding slides C, will operate said cutter slides to open and close 5 the die.

By adjusting pivot bolt 22 the size of die required, within the limits of the size of the head, can be secured as will be readily understood.

16 The cutter holding slides are formed with notches n on their sides in which the adjacent corner of the adjacent slide is adapted to stand when the die is closed, as in the Fisher patent above referred to, thus permitting 15 of a larger number of cutters to the die-head and the use of the tangential form of cutter or chaser.

The body A is provided with a cylindrical axial projection 28 on its face which serves 20 as a journal or bearing for the cam ring B. It is cut into sections by the grooves 13, which cut through it, thus dividing said ring into segmental sections or abutment blocks against which said cam ring bears 25 and by which it is supported. The outer faces of said abutment blocks are flush with the leading faces of the chasers, (see Fig. 5). As the serration in the chaser next to its face does the main cutting, the 30 force applied at this point is the greatest and causes the greatest strain both in a tangential and radial direction. The particular construction shown and described whereby the cutter holding blocks are supported 35 against this strain both by the abutment blocks and the particular arrangement of grooves results in a largely increased efficiency in the operation of the die and constitutes a leading feature of my said invention.

40 The retaining ring 11 is sunk into the head body of the cam ring B and body A, as shown, with its outer face flush with the outer faces of said parts and is provided 45 with concentric arcuate projections 29 extending into the spaces between the abutment blocks 28 just inside but not forming a continuation of the cam ring bearing. These projections form closures between the 50 abutment blocks 28 bearing upon the surface M of stem of chaser holding slide and thus prevent dust and chips from entering the cam bearings but do not serve as any part of the journal for the cam annulus B 55 which is furnished by the abutments 28 as above described.

In work of the character for which this die head is particularly intended unusual strain, both in radial and tangential directions, comes upon the cutters and is transmitted to the cutter-holders and the cutter

holding supports. In the construction here- 65 tofore employed more or less binding and resulting trouble has been experienced. By the construction herein shown and de- 70 scribed, wherein the base of each holder is supported on the body by a tongue and groove connection with its ways, and the face of one side of the cutter holding end is supported against a rigid abutment in 75 line with its leading serration, of cutting edge, these troubles are overcome and a very efficient and durable cutter-head for the purpose provided.

Having thus fully described my said invention what I claim as new and desire by Letters Patent, is:

1. A cutter head having a groove formed therein with an underlying narrower groove, a chaser holder having a body proportioned 80 for sliding fit within the groove and a T-rib proportioned for sliding fit in the underlying groove, and gibs rigidly secured within the groove and proportioned for sliding fit between the body and the T-rib. 85

2. A cutter head having a groove formed therein with an underlying narrower groove, a chaser holder having a body proportioned for sliding fit within the groove and a T-rib proportioned for sliding fit in the underlying groove, and gibs bearing upon and retaining the T-rib and slidably supporting the body. 90

3. A cutter head having a groove formed therein with an underlying narrower groove, 95 a chaser holder having a body proportioned for sliding fit within the groove and a T-rib proportioned for sliding fit within the underlying groove, removable gibs proportioned for sliding fit between the body and the T-rib, and screws inserted from the face of the head opposite the groove and terminating in and rigidly securing the gibs. 100

4. A cutter head having a groove formed therein with an underlying narrower groove, a chaser holder having a body proportioned for sliding fit within the groove and a T-rib proportioned for sliding fit within the underlying groove, removable gibs bearing upon and retaining the T-rib and slidably supporting the body, and screws inserted from the face of the head opposite the groove and terminating in and rigidly securing the gibs. 110

In witness whereof I have hereunto set 115 my hand and seal at Waynesboro, Pennsylvania, this 8th day of August, A. D. nineteen hundred and eighteen.

GUSTAF ARVID ANDERSON. [L. S.]
